(57) **CLAIM**

The ornamental design for a medical probe, as shown and described.

DESCRIPTION

FIG. 1 is a first perspective view of a medical probe;
FIG. 2 is a second perspective view thereof;
FIG. 3 is a front view thereof, the opposite side being a mirror image of the side shown herein;
FIG. 4 is a left side view thereof;
FIG. 5 is a right side view thereof;
FIG. 6 is a top view thereof;
FIG. 7 is a bottom view thereof;
FIG. 8 is a cross-sectional view taken along line 8-8 in FIG. 3 in which the internal mechanism is omitted thereof; and,
FIG. 9 is a cross-sectional view taken along line 9-9 in FIG. 4 in which the internal mechanism is omitted thereof.
